Primary Examiner — Patricia A Palasik(74) *Attorney, Agent, or Firm* — Husch Blackwell LLP(57) **CLAIM**

The ornamental design for a transducer fairing, as shown and described.

DESCRIPTION

FIG. 1 is a top left side perspective view of an embodiment of a transducer airing showing our new design;

FIG. 2 an enlarged top right side perspective view thereof;

FIG. 3 is a front view thereof;

FIG. 4 top view thereof;

FIG. 5 is a left side view thereof;

FIG. 6 is a right side view thereof;

FIG. 7 is a bottom view thereof; and,

FIG. 8 is a rear view thereof.

The transducer fairing thereof is shown with a symbolic break in its length. The appearance of any portion of the transducer fairing between the break lines forms no part of the claimed design.
